(57) **CLAIM**

The ornamental design for a game machine, as shown and described.

DESCRIPTION

FIG. 1 is a front view of a game machine showing our new design;

FIG. 2 is a rear view thereof;

FIG. 3 is a right side view thereof;

FIG. 4 is a left side view thereof;

FIG. 5 is a top plane view thereof;

FIG. 6 is a bottom plan view thereof;

FIG. 7 is a perspective view thereof;

FIG. 8 is another perspective view thereof;

FIG. 9 is a sectional view taken along line 9—9 in FIG. 1; and,

FIG. 10 is a sectional view taken along line 10—10 in FIG. 3.

The broken lines, which define the bounds of the claimed design, form no part thereof. The broken lines environment is for illustrative purpose and forms no part of the claimed design.
